Milton Sibbets. ATTORNEY

UNITED STATES PATENT OFFICE.

LIONEL M. WOOLSON, OF DETROIT, MICHIGAN, ASSIGNEE TO PACKARD MOTOR CAR COMPANY, OF DETROIT, MICHIGAN, A CORPORATION OF MICHIGAN.

HYDROCARBON-MOTOR.

1,382,946.

Specification of Letters Patent. Patented June 28, 1921.

Application filed October 16, 1919. Serial No. 881,042.

To all whom it may concern:

Be it known that I, LIONEL M. WOOLSON, a citizen of the United States, and resident of Detroit, Wayne county, State of Michigan, have invented certain new and useful Improvements in Hydrocarbon-Motors, of which the following is a specification.

This invention relates to hydrocarbon motors and particularly to mixture devices therefor.

In combustion heater devices such as illustrated in my pending application Serial No. 323,627, means are provided for breaking up the mixture just before it enters the combustion chamber to thereby cause the mixture to more readily ignite. One of the objects of the present invention is to improve upon the form of means for thus breaking up the mixture entering the combustion chamber of a heater device such as illustrated in said pending application.

The invention may be adapted to other forms of devices and it is not intended that it shall be limited to the use above referred to.

Other objects, uses and advantages of the invention will appear from the following description taken in connection with the drawings which form a part of this specification and in which

Figure 1 is a sectional view of a heater device embodying the invention; and

Fig. 2 is a transverse section on the line 2-2 of Fig. 1.

Referring to the drawings, 10 illustrates a section of an intake pipe or header of a hydrocarbon motor and 11 is a chamber or jacket surrounding part of said intake pipe being thus arranged in heating relation to said pipe. This chamber 11 may be called a combustion chamber and part of said chamber or a communicating chamber is formed in a casting 12 in which an igniter in the form of a spark plug 13 and an observation window 14 are mounted. The casting 12 is threaded into the wall of the jacket 11 as shown at 15, this being merely for convenience in manufacture.

A pipe or conduit 16 for carrying mixture to the combustion chamber 11 may be connected to any suitable carbureting device, not shown. This pipe will carry a mixture of gasoline, or other liquid fuel, and air, and because the pipe may be more or less exposed to the cooling effect of the surround-

ing atmosphere, some of the particles of gasoline may condense and be carried through in the form of minute liquid globules or particles. For the purpose of breaking up these globules or particles means are arranged between the pipe 16 and the chamber 11. This means principally comprises a nozzle 17, a surrounding chamber or cup 18, and a second surrounding chamber 19. The nozzle 17 is in communication with the pipe 16 through a passage 20 in an elbow 21, the nozzle in the form shown being integral with said elbow. A connecting nut 22 binds the end of the pipe 16 to the elbow 21.

The elbow 21 is threaded into the upper part of the cup 18, which cup is formed with a flange 23 at its upper end for threading onto the upper end of the second surrounding chamber 19. This chamber 19 is also formed as an integral part of the casting 12 and it has an inwardly extending annular flange 24 with an opening or passage 25 therein into which a nose 26 on the cup 18 projects. The nose 26 has a vertical passage 27, the inlet end of which is in direct line with the passage 28 formed in the nozzle 17 and the lower end of passage 27 is in the form of several branches 29 which extend laterally into the chamber 11 below the flange 24 and opening 25.

The cup 18 is also provided with a series of openings or ports 30 above the lower end of the nozzle and they are shown as located near the upper end of the cup. These ports 30 place the upper part of the cup in communication with the upper part of the surrounding chamber 19 and the passage 25 in the latter chamber in turn places that chamber in communication with the combustion chamber 11.

The chamber 11 above referred to is in communication with the interior of the intake pipe 10 through a perforated plug 31 and when the motor to which the intake pipe is connected is turned over or started, either by hand cranking or by an electric starting motor, a depression is created in the intake pipe and this is communicated to the combustion chamber 11, which thereupon draws mixture from the carburetor above referred to, through the mixture pipe 16. As this mixture discharges from the passage 28 in the nozzle 17, the heavier liquid particles by their inertia pass

directly into the passage 27 and outwardly through the lateral ports 29. Some of the air of this mixture, however, spreads at the end of the nozzle 17 and passes upwardly 5 in the cup 18 and outwardly through the ports 30 into the chamber 19. This air is then drawn through the passage 25 which is somewhat restricted at this point due to the projection into it of the nose 26, and as this 10 air rushes past the ports 29 it picks up and breaks to pieces the particles of gasolene or liquid fuel which is being discharged by those ports. Thus a very thorough mixture is carried into the chamber 11 and passes 15 rapidly by the igniter 13 and is thereby fired in the chamber 11.

Other forms of devices than that shown may be made without departing from the spirit or scope of the invention.

20 Having thus described my invention, what I claim and desire to secure by Letters Patent is:

1. A combustion heater device comprising a combustion chamber, means for igniting the charge therein, a mixture nozzle, a chamber surrounding said nozzle and having openings at opposite ends thereof, and a second chamber surrounding the first chamber and having a passage for the mixture 25 adjacent one of the outlet openings of the first chamber.

2. A combustion heater device comprising a combustion chamber and means for igniting the charge therein, a mixture inlet including a downwardly extending nozzle, a chamber surrounding said nozzle and having a passage in line with said nozzle and communicating with the interior of the combustion chamber, said surrounding chamber 35 also having outlet openings in its upper portion, and another chamber surrounding the

first chamber and with which the openings at the upper end of the first surrounding chamber communicate, said second surrounding chamber having a passage leading to the 45 combustion chamber in proximity to the lower outlet opening from the first chamber.

3. In a combustion heater device, the combination with a combustion chamber and means for igniting the charge therein, of a 50 downwardly extending nozzle, a cup surrounding said nozzle and having an outlet below the outlet of said nozzle and in line therewith, said cup also having lateral openings above the lower end of said nozzle, and 55 a chamber surrounding said cup and having its interior in communication with said cup through the upper openings, and said chamber having an outlet adjacent the lower outlet from said cup.

4. A combustion heater device comprising a combustion chamber and means for igniting the charge therein, a chamber having an outlet opening communicating with said combustion chamber, a cup in said second 65 chamber having an outlet nose extending through said opening and having lateral openings into said second chamber, and inlet means for said cup.

5. A combustion heater device comprising 70 a combustion chamber and means for igniting the charge therein, a chamber having an outlet opening communicating with said combustion chamber, a cup in said second chamber having an outlet nose extending 75 through said opening and having lateral openings into said second chamber, and inlet means including a nozzle extending into said cup in line with its outlet nose.

In testimony whereof I affix my signature. 80

LIONEL M. WOOLSON.
